UNITED STATES PATENT OFFICE.

CHARLES A. SNYDER, OF PHILADELPHIA, PENNSYLVANIA.

MACHINE AND PROCESS FOR RECLAIMING SILK.

Application filed July 2, 1923. Serial No. 648,941.

To all whom it may concern:

Be it known that I, CHARLES A. SNYDER, a citizen of the United States, residing at Philadelphia, in the county of Philadelphia 5 and State of Pennsylvania, have invented new and useful Improvements in a Machine and Process for Reclaiming Silk, of which the following is a specification.

My invention relates to a new and useful 10 improvement in a machine and process for reclaiming silk, and has for its object to provide a simple and effective arrangement for unraveling stockings and other knitted goods moistening and ironing silk threads during 15 the unraveling.

A further object of my invention is to separate the silk and cotton or other threads during the process of unraveling and winding each upon a separate drum or spool.

Another object of my invention is to provide a process for reclaiming silk from knitted "clippings" which consists of drawing upon the threads of a "clipping" held under a slight tension and causing the drum 25 holding the clipping to be revolved during the unraveling of the "clipping."

A further object of this invention is to provide a drum to receive tubular "clippings" and associate with said drum a retarding weight preferably having mobile 30 characteristics whereby the drum will be prevented from racing.

A still further object of this invention is to provide a machine which will unravel 35 and treat both ordinary hose "clippings" and full fashioned hose "clippings" and remove the reinforce thread during the unraveling.

With these ends in view, this invention 40 consists in the details of construction and combination of elements hereinafter set forth and then specifically designated by the claims.

In order that those skilled in the art to 45 which this invention appertains, may understand how to make and use the same, I will describe its construction in detail, referring by numerals to the accompanying drawings forming a part of this application, in which:—

Fig. 1 is an end view of a machine made 50 in accordance with my improvements illustrating the course of the threads when unraveling ordinary and full fashioned hose clippings.

Fig. 2 is a front view thereof partially broken away so as to indicate greater width and the full fashioned clipping omitted.

Fig. 3 is an enlarged view of a portion of the heating and ironing element.

Fig. 4 is a cross section of Fig. 3.

Fig. 5 is an end view of the unwinding drum a portion being broken away and showing the retarding weight.

Fig. 6 is a side view of Fig. 5, a portion thereof also being broken away and sectioned to show the retarding weight and construction of the drum.

Fig. 7 is a diagrammatical view showing the course of the threads in unraveling reinforced hose "clipping."

In carrying out my invention as here embodied I provide a frame which consists of the legs 1 and the uprights 2 which are joined together by curve reaches 3 it being understood that these parts are in duplicate when set upon each side of the machine suitably connected together serving to support the operating parts of the machine.

In the construction of the machine here shown I have provided for a double capacity and therefore in the description of operation of this machine reference will be had to only one set of these working parts the other set being an exact duplicate.

Secured to each of the uprights 2 is a supporting arm 4 projecting outwardly and downwardly and terminating in open bearings 5; these bearings being for the reception of the ends of the shaft 6 upon which the unwinding drum 7 is mounted. This drum may be either secured to the shaft 6 so that they may revolve together or it may be loosely fitted upon said shaft so that it may revolve independent thereof, and this drum carries in its interior a mobile weight 8 preferably consisting of a quantity of shot or small metallic balls, the object of which will be hereinafter explained.

9 represents two arms one projecting from each of the uprights 2, said arms terminating in the trays 10 or having such tray secured thereto; this tray has secured therein a feeder 11 preferably made of wicking or other suitable fabric and held in place by the hooks 12 projecting from the front edge of said tray. The object of this arrangement is to convey a suitable liquid placed within the tray to the outer edge of the wick for transmission to the passing threads.

13 represents a steam chest formed with or secured to a condensing chamber 14 which latter is supported by the posts 15 seated upon the arms 9. This steam chest is oblong and set at an angle so that its outer surface will serve as an ironing surface and steam is conveyed to the interior thereof by a pipe 16 leading from any suitable source of live steam and in order that the waters of condensation may readily pass through said chest to prevent the undue cooling thereof, one or more outlets 17 lead from the lower portion of the chest to the interior of the condensing chamber 14. As the waters of condensation accumulate in the condensing chamber they are blown off through the pipe 18, the flow through said pipe being controlled either by a hand valve or by an automatic relief valve.

19 represents two bracket arms each being supported by the uprights 2 and in each of these arms are formed two open bearings 20 and 21 for the reception of the spindles 22 and 23 respectively; the spindle 22 carrying the winding drum 24 while the spindle 23 carries the winding drum 25. Also upon each of these spindles is secured a friction disc 26, these friction discs bearing against the friction roll 27 which latter is mounted upon the shaft 29 which is fitted to revolve in the open bearings 30 formed in the outer ends of the brackets 31, said brackets projecting from the uprights 2. The shaft 29 may be revolved from any suitable source of power so as to give to the friction roll 27 the proper direction and speed for revolving the winding drums 24 and 25, whereby the latter may take on the threads being unraveled as hereinafter described.

32 are two arms adjustably secured to the legs 1 as indicated at 33 and these arms are connected by a guide rod 34 which serves to guide the thread from a certain class of work.

35 are two standards the lower end of each of which is adapted to fit within sockets 36 formed in the upper ends of the uprights 2 and these standards support the superstructure 37 along the edges of which are secured the hooks 38 from which hooks certain classes of work may be suspended.

From the foregoing description the operation of my invention will be obvious as follows:

For the reclaiming of silk thread or the like from what is known in the trade as ordinary hose "clippings" it is necessary to so mount the "clippings" that while it may be revolved during the unraveling of the threads a certain tension can be uniformly maintained thereon and provision can be made for simultaneously unraveling the silk and cotton threads from which such hose are usually made. This can be accomplished by drawing the "clippings" over the unraveling

drum 7 as indicated at 39 and leading the silk thread 40' upward over the feeder 11, the ironing surface of the steam chest and over the adjustable guide 40 which latter consists of a bar set in the sockets 41 and maintained in position by the screws 42. This thread then passes to the winding drum 24 and as this drum is revolved by friction it will maintain a uniform pull upon the thread without at any time exerting a breaking tension.

The cotton thread 43 is carried upward from the "clipping" over the guide rod 44 supported upon the brackets 45 and thence over the guide 46 onto the winding drum 25 and this drum also being driven by friction is free to take up the cotton thread at whatever speed it may be unraveled, assuming that the drum is normally being revolved at a speed greater than the maximum of said thread.

This arrangement of the friction revolved winding drums and retarded unravelling drum is essential to the proper handling of the material to be treated since the silk and cotton threads do not unravel at the same rate nor at a fixed ratio; therefore by my arrangement this peculiarity is provided for since the unwinding drums 24 and 25 will revolve at whatever speed is necessary to receive the unravelling threads.

To unravel and treat what is known in the trade as full fashion "clipping" it is only necessary to suspend such "clipping" indicated at 47 from the hooks 38 and draw the threads therefrom downward around the guide 34 and then around the unwinding drum 7 after which the threads will be treated in the same manner as that described in connection with the threads 40' and 43. Where the machine is constructed of sufficient width both classes of work may be performed at one and the same time, but where it is desirable to unravel and treat the threads from a reinforced hose "clipping", such "clippings" are mounted upon forms 48 and the silk thread 49 is led over one of the hooks 38 and down under the guide 34 and then around the unwinding drum 7 after which it is led upward in the same manner as the thread 40' as before described. In this case the thread 50 which is being unraveled from the reinforced section 51 is also led upward over one of the hooks 38 and downward and finally attached to the auxiliary drum 52 which is of the same general construction as the drum 7 having a number of shot or balls 53 therein to give the retarding action thereto, said drum being loosely mounted upon the shaft 54 having a pulley 55 secured to said shaft to which power may be conveyed from any suitable source for revolving said pulley and shaft. This arrangement will permit the taking up of the reinforced

thread 50 as fast as the thread 49 is unraveled but will prevent any undue pull upon the thread 50.

When desired this last described attachment may be so embodied in the machine as to permit the unraveling of either ordinary hose "clippings", full fashioned hose "clippings" or reinforced hose "clippings" or all three at one and the same time.

10 Of course I do not wish to be limited to the exact details of construction as herein shown as these may be varied within the limits of the appended claims without departing from the spirit of my invention.

15 Having thus fully described my invention, what I claim as new and useful is:—

1. A silk reclaiming machine comprising in combination a frame; an unraveling drum; a shaft upon which said drum is mounted; open bearings carried by the frame in which said shaft is journaled; a tray mounted upon the frame; an absorbent strip located in said tray and projected beyond the edge of the same; a steam chest one surface of which is adapted to iron a thread drawn thereover; a winding drum; means to revolve said drum by friction; a

guide interposed between the steam chest and said winding drum; a second winding drum; and means for revolving the last 30 named drum by friction.

2. In combination with a machine of the character described one or more holders for reinforced hose clippings; an unraveling drum; means for retarding the rotation of 35 said drum; an auxiliary drum; means for retarding the rotation of the latter; and means for guiding the primary threads from the clippings to the unraveling drum; and means for guiding the reinforcement 40 threads from the clipping to the auxiliary drum.

3. The process of reclaiming silk from a knitted clipping consisting of placing said clipping on a drum, winding the thread 45 from said clipping on a suitable device from the drum, the winding of said thread causing the clipping and drum to revolve, and retarding said drum during the revolving 50 thereof.

In testimony whereof, I hereunto affixed my signature.

CHARLES A. SNYDER.
